(57) **CLAIM**

The ornamental design for a portion of a display screen with graphical user interface, as shown and described.

DESCRIPTION

FIG. 1 is a front view of a first embodiment of a portion of a display screen with graphical user interface showing our new design;

FIG. 2 is a front view of a second embodiment of a portion of a display screen with graphical user interface showing our new design;

FIG. 3 is a front view of a third embodiment of a portion of a display screen with graphical user interface showing our new design;

FIG. 4 is a front view of a fourth embodiment of a portion of a display screen with graphical user interface showing our new design; and,

FIG. 5 is a front view of a fifth embodiment of a portion of a display screen with graphical user interface showing our new design.

The broken lines in FIGS. 1-5 illustrate portions of an electronic device, the display screen, and portions of the graphical user interface. None of the broken lines form part of the claimed design.

1 Claim, 5 Drawing Sheets
